UNITED STATES PATENT OFFICE.

CHARLES A. MATHIESEN AND JOHN C. SCHRADER, OF NEW YORK, N. Y.

DESIGN FOR SEAL-PRESSES.

Specification forming part of Design No. 6,806, dated August 19, 1873; application filed August 7, 1873.

To all whom it may concern:

Be it known that we, CHARLES A. MATHIESEN and JOHN C. SCHRADER, of the city, county, and State of New York, have invented a new and original Design for Seal-Presses; and we do hereby declare the following to be a full, clear, and exact description thereof, which will enable those skilled in the art to make and use the same, reference being had to the accompanying drawing forming part of this specification, which drawing represents a side view of our press.

Our design consists in a bird resting upon the inclined trunk or branch of a tree. The handle of our press forms the continuation of a scroll emanating from the bill of the bird.

In the drawing, the letter A designates the

base of our seal-press, which is ornamented by foliage. From this base rises the standard, which consists of the inclined trunk or branch B of a tree, that forms the support for a bird, C. The handle D of our press is made in the form of a scroll, and it appears as if it was continued to the bill of the bird C.

What we claim as new, and desire to secure by Letters Patent, is—

The design of a seal-press, as herein shown and described.

CHARLES A. MATHIESEN.
JOHN C. SCHRADER.

Witnesses:

W. HAUFF,
P. E. FAAZ.
